UNITED STATES PATENT OFFICE.

HENRY F. COX, OF ALTOONA, PENNSYLVANIA.

SWITCH ATTACHMENT.

SPECIFICATION forming part of Letters Patent No. 232,176, dated September 14, 1880.

Application filed July 20, 1880. (No model.)

To all whom it may concern:

Be it known that I, HENRY F. COX, a citizen of the United States, residing at Altoona, in the county of Blair and State of Pennsylvania, 5 have invented certain new and useful Improvements in Switch Attachments; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

Figure 1 represents a plan view of an automatic switch set for the main line and having my improvements applied thereto. Fig. 2 represents a similar view, the switch being set for the siding. Fig. 3 represents a detail view, on an enlarged scale, through the line xx of Fig. 2; and Fig. 4 represents a similar view, but with the operating parts in different relative positions. Fig. 5 represents an enlarged detail view through the line yy of Fig. 1; and Fig. 6, a side elevation of the drum or wheel, 25 showing the guide-piece for the arm or finger.

My invention has relation to automatic railroad-switches and their attachments; and it consists in a novel construction and arrangement of an attachment to an automatic switch, 30 whereby the switch may be operated from a distant point, and yet so arranged as to permit of an automatic action of the switch by a passing train in the event of its being misplaced; and it further consists in certain details of construction, which will be hereinafter described, 35 and then pointed out in the claims.

In the drawings, A represents an automatically-operating switch, and which consists, in connection with the main-track rails a b , of 40 the switch-rails c d , the automatically-operating rail e , switch-rods f g , cranks f' and h' , and connecting-shaft h .

The operation of this switch is such that upon the switch being set wrong or misplaced 45 for a train coming in the direction indicated by the arrow, Fig. 2, the flange of the advanced wheel will strike the pivoted rail e , (which lies adjacent to the rail b), forcing it inward or between the rails, (see Fig. 1), and causing the 50 switch to open by the rail e having connection with rod g , crank h' , shaft h , crank f' , and rod f , and thereby allowing the train to pass.

This construction of switch is well known, and is not, therefore, necessary to be here minutely described, my invention consisting in 55 providing this form of switch or any other form of automatic switch operated upon like principles with an attachment by means of which the switch may be operated by a rod or chain or equivalent at a distance without interfering with its proper manipulation by hand or by the action of the train itself.

In carrying out my invention, therefore, I provide the connecting-shaft h , by means of which the switch-rods f g are operated, with a 60 loosely-mounted drum or wheel, B, carrying an arm or finger, C, of novel construction. This arm C is illustrated in Figs. 3, 4, and 5, and is mounted upon the drum B, upon a guide-piece, b' , the arm being formed with a corresponding guide-slot, b^2 , thereby allowing to the arm C a movement in the line of its length. The outer end of the arm C is provided with thumb and finger projections c^2 c^3 , for a purpose shortly to be described. 70

D represents a stationary eccentric and guide-way arranged at the side of drum B in any suitable and known way, for the purpose of receiving the pin d' , projecting from the arm C. 75

E represents a lever of peculiar construction 80 rigidly attached to the operating-shaft h . Near its outer end this lever is bent or curved, at e' , so as to extend over and across the face or width of eccentric guide-slots D; and at this point, on the side next the drum B, is secured a 85 pivoted arm, F, with its pivotal point at G, the construction of which will be pointed out in connection with its operation.

i represents the ordinary weighted lever of 90 an automatic switch, the switch-rod being connected thereto at some distance from the pivotal point, the effect of which and of the weighted end being to prevent its being inadvertently or accidentally misplaced or being thrown by a passing train. 95

Upon the drum or wheel B is secured a wire, rope, or chain, or equivalent, by which the wheel may be operated, and which is led to a signal cabin or tower; or the switch may be actuated from any other suitable and desirable 100 point.

The operation of my device is simple and easily understood, and is as follows: In Fig. 1 the switch is shown set for the main track,

which is open and the main line unbroken. In this position the switch-lever E is at the outer end of its throw, and the arm or finger C, carried by the drum B, engages the pivoted arm F of the switch-lever E. When, however, it is desired to set the switch for the siding, the rod or chain passing over the drum B is worked so as to revolve the drum, and this carries the switch-lever E to the position shown in Figs. 2 and 3. This operation just described is effected as follows: Upon the drum B being revolved in the direction indicated by the arrow, Fig. 5, the arm of finger C of the drum engages the lever E by its shorter projection c^2 coming in contact with the pivotal arm F of the lever E, the drum still continuing to revolve till the lever E reaches a horizontal position, when the pin d' of the arm C will enter a cam portion, d^2 , of the guide-way D and cause the arm C to be thrust radially outward at the same time that it is revolving, thereby completely embracing the peculiarly-formed head of the pivoted arm F of the lever E. The arm C will thus engage the switch-lever E until said lever has reached the position shown in Fig. 3, when the pin d' of the arm C enters the cam portion d^3 of the guide-way D and withdraws the arm C radially inward, thereby disengaging the switch-lever. In this condition (Figs. 2 and 3) the switch is free to be operated automatically by a train coming in the direction indicated by the arrow, Fig. 2; or the switch may be operated by hand without interfering with the attachment to the switch. In the event of the switch being operated by a passing train or by hand so as to carry the switch-lever E to the other end of its throw and set the switch for the main line, the drum B is made to revolve so as to bring the arm C to the position shown in Fig. 5, and in the direction opposite to that indicated by the arrow in the last-named figure, where it will engage the switch-lever E. This peculiar operation is effected as follows: When the pin d' of the arm C reaches the cam d^2 the arm C will be drawn inwardly sufficiently far to enable it to pass the swell f^2 of the head of the pivoted arm F. This it will do by the lower projection, c^2 , striking the portion f^2 of the arm F and causing said arm, by the peculiar arrangement of its pivot, to be oscillated outwardly, when the projection c^2 of the arm C will pass below the head f^2 , thereby engaging the lever E, when it is again in position to be operated from the signal-cabin or other point in the manner before set forth.

When the switch is in the position shown in Fig. 2 and it is desired to reset the switch from the signal-cabin so as to leave the main line unbroken, the operation is as follows: The arm C and switch-lever E are in the relative positions shown by Fig. 3. The arm C, carried by the drum B, is made to revolve, when said arm C will be carried from the position in Fig. 3 to that in Fig. 4, where the pivoted arm F of the

switch-lever takes into the arm C, and, upon the arm C still continuing to revolve, the arm C and switch-lever E will be brought back again to the position indicated in Fig. 5.

Having described my invention, what I claim as new, and desire to secure by Letters Patent of the United States, is—

1. In a railroad-switch, a connecting-shaft uniting the switch-rods and provided with a switch-lever and with a loosely-mounted drum or wheel carrying an arm or finger adapted to engage and disengage the switch-lever E, substantially as and for the purpose set forth. 75

2. In a railroad-switch, a connecting-shaft uniting the switch-rods and provided with a loosely-mounted drum or wheel carrying an arm or finger adapted to engage and disengage the switch-lever at one end of its throw and to engage the same at the other end or limit of its throw, substantially as and for the purpose set forth. 80

3. The combination of the switch-rails e , d , and e , switch-rods f and g , and cranks f' and h' , connected by the operating-shaft h with a loosely-mounted drum or wheel carrying an arm or finger adapted to engage and disengage the switch-lever, substantially as and for the purpose set forth. 90

4. An attachment to an automatic switch, consisting of a drum or wheel loosely mounted upon an operating-shaft and carrying an arm or finger adapted to operate a switch-lever, all being so arranged with respect to the switch-lever that a train, in passing through the switch when misplaced, will be free to operate it without operating said drum or wheel and its arm, substantially as set forth. 95

5. A drum or wheel loosely mounted upon the operating-shaft of a railroad-switch and carrying an arm or finger having a limited movement in the line of its length, and provided with a pin working within an eccentric, whereby the arm disengages and engages a switch-lever at one end or limit of its throw and engages the same at the other limit of its throw, substantially as specified. 105

6. A drum or wheel loosely mounted upon the operating-shaft of a railroad-switch and carrying an arm or finger having a limited movement in the line of its length, and provided with a pin working within an eccentric, in combination with a switch-lever having a pivoted arm at or near its outer end, whereby the arm or finger of the drum disengages and engages the pivoted arm of the switch-lever at one end or limit of its throw and engages the same at the other limit of its throw, in the manner substantially as set forth. 115

In testimony whereof I affix my signature in presence of two witnesses.

HENRY F. COX.
